UNITED STATES PATENT OFFICE.

JAMES C. FRENCH, OF KENOSHA, WISCONSIN, ASSIGNOR TO FREDERICK C. AUSTIN,
OF CHICAGO, ILLINOIS.

TRENCHING-MACHINE.

1,377,333.

Specification of Letters Patent. Patented May 10, 1921.

Application filed September 28, 1914. Serial No. 863,854.

To all whom it may concern:

Be it known that I, JAMES C. FRENCH, a citizen of the United States of America, and resident of Kenosha, Kenosha county, Wisconsin, (510 Exchange street,) have invented 5 a certain new and useful Improvement in Trenching-Machines, of which the following is a specification.

My invention relates to trenching machines of that kind in which a movable beam is provided with an endless series of buckets for cutting the trench while the machine moves slowly forward in the well known manner.

Generally stated, the object of my invention is to provide a trenching machine which will cut either a wide or a narrow trench without the necessity of changing or removing the buckets thereof.

More specifically considered, the object of my invention is to provide a machine of this kind having cutters for producing a trench which is wider than the buckets, but which are removable when it is desired to 25 cut a narrower trench, and which are shaped or formed in such manner that each cutter discharges the dirt into the path of the buckets, the said cutters being arranged in two parallel series at opposite sides of the 30 endless series of buckets.

It is also an object to provide certain details and novel features of construction and combinations tending to increase the general efficiency and desirability of a trenching machine of this particular character.

To the foregoing and other useful ends my invention consists in matters herein-after set forth and claimed.

In the accompanying drawings—

Figure 1 is a side elevation of the lower end portion of the digging beam and endless series of excavating buckets of a trenching machine embodying the principles of my invention.

Fig. 2 is an enlarged front elevation of one of said buckets, showing the two cutters or auxiliary buckets disposed at opposite sides thereof, this view being in the nature of an enlarged section on line 2—2 in Fig. 1.

Fig. 3 is an outer side elevation, on a larger scale, of the left hand cutter shown in Fig. 2, showing the adjacent portions of the link belt to which said cutter is secured.

Fig. 4 is an enlarged detail view of one 55 of the buckets and the two cutters therefor,

looking in the direction of the arrows of the line 4—4 in Fig. 1.

Fig. 5 is a cross section of the trench cut by said buckets and cutters, showing the shoulders formed by the cutters at opposite 60 sides of the bottom of the trench.

Fig. 6 is a similar view showing the shape of the trench when the said cutters or auxiliary buckets are not used.

As thus illustrated, my invention comprises a digging beam A of any suitable character, it being customary to support this beam for up and down movement at the rear end of the trenching machine, whereby the beam swings about a horizontal axis disposed at or near its upper end, and the said axis extending transversely of the ditch. Sprockets (not shown) are provided at the upper end of the beam and rotary supports B at the lower end of said beam, and a pair of link belts C are arranged to travel around said sprockets and members. The excavating buckets D are removably secured to the links of said belts, by means of ears or lugs d inserted between the links, the buckets 70 serving to space the two belts the proper distance apart at intervals along the latter. These buckets are preferably open at their upper or inner sides d¹, but have rounded or curved bottom or outer walls d² which face 75 the inclined surface X upon which the buckets operate as they travel upward. Each bucket is also provided with teeth or cutters d³ for pulverizing or tearing up the soil. The angle at which the buckets travel 80 upwardly is sufficient to prevent the loose dirt from falling out of the rear end of each bucket, and the load is dumped when the bucket turns upside down at the upper end of the beam, in the usual and well known 85 manner.

The construction thus far described is capable of cutting a trench which in cross section is like the one shown in Fig. 6, this trench being practically no wider than the 100 buckets. It is sometimes desirable, however, to cut a wider trench, and for this purpose cutters or auxiliary buckets E are provided and attached to the belts C at points between the buckets D, whereby a relatively 105 wide trench of the kind shown in Fig. 5 may be produced when necessary or desirable. Referring to Figs. 2 to 4 inclusive, it will be seen that each cutter E is shaped somewhat like a bucket, being formed with a for- 110

ward cutting edge e , an outer or bottom wall e^1 that extends rearward to the rear edge e^2 of the cutter, and having side walls e^3 and e^4 , whereby each cutter tapers rearwardly when viewed from the side, as shown in Fig. 3, causing the dirt to be thrown into the plane of the upwardly traveling portions of the link belt. When viewed from above, as shown in Fig. 4, it will be seen that the outer wall e^3 curves inwardly toward the rear, thus causing the dirt to be thrown inwardly toward the adjacent link belt. Also, and in order that the dirt loosened up by the cutter E may be thrown directly into the path of the upwardly traveling buckets D the walls e^1 and e^4 are formed with a rear edge e^5 which extends at an angle to the front edge e , and also at an angle to the wall e^3 and the adjacent link belt, the effect being to provide the cutter E with a rear opening e^6 for discharging the dirt inwardly and directly into the path of the excavating buckets. Each cutter E has its wall e^4 provided with a shank or attaching portion e^7 which is removably secured in any suitable manner, but rigidly of course, between the links of the adjacent belt. Thus the cutters E extend laterally at each side of the endless series of excavating buckets D, thereby producing a trench which is wider than said buckets; but as these cutters or auxiliary buckets E are preferably smaller than the buckets D, and do not cut as deeply as the said buckets, it follows that the bottom of the trench is formed with a pair of shoulders Y, as shown in Fig. 5, and these shoulders are, of course, also formed at each side of the inclined surface X at the end of the trench; and as the buckets and cutters travel up this inclined surface the dirt loosened up or cut away by the cutters E is pushed off from said shoulders and into the path of the excavating buckets D, in the manner described. When it is desired to cut a trench of the character shown in Fig. 6, the cutters E are detached from the link belts.

From the foregoing it will be seen that by my invention I provide a trenching machine having provisions for forming relatively wide and narrow trenches, and that the change from one width of trench to the other is accomplished without removing or changing the excavating buckets.

55 Thus the trench is, in effect, composed of three parallel channels, the middle channel being cut by the buckets D, and the two outside channels being cut by the scoop-shaped cutters E, and one channel merging into the other to form the entire width of the trench.

It is an important consideration, it will be seen, that the front end of the auxiliary cutter E is some distance behind the front end of the link C to which it is attached, 60 as in this way the cutter is pulled at its

front end, or dragged, so to speak, in a manner that is more satisfactory than would be the case if the cutter was secured at its rear end to the chain, or even connected at its middle portion to the link belt, as in such case the front end of the cutter would extend ahead of the point of attachment on the chain. Moreover, the cutters E discharge the dirt at their rear ends, and these rear ends can swing away from the link belts 75 while the latter are traveling around the sprocket wheels, so that both the buckets and the auxiliary cutters are adapted to discharge the dirt from their rear ends.

What I claim as my invention is:— 80

1. An excavator comprising laterally spaced endless chains, main excavating elements mounted between the chains, scoop-shaped auxiliary excavating elements carried by the chains between which the first-mentioned excavating elements are mounted, said auxiliary excavating elements being open at their rear ends to discharge inwardly and projecting laterally from the sides of the chains and working beyond the 90 sides of the first-mentioned excavating elements.

2. An excavator comprising laterally spaced endless chains, main excavating elements mounted between the chains, auxiliary excavating elements carried by the chains between which the first-mentioned excavating elements are mounted, said auxiliary excavating elements being open at their rear ends to discharge inwardly and projecting laterally from the sides of the chains and working beyond the sides of the first-mentioned excavating elements and said auxiliary excavating elements being scoop shaped and comprising a bottom having sides and a back, a shank extending from the top of the inner side and fitting between adjacent chain links, and fasteners passing through said links and the shank therebetween. 100

3. An excavator comprising laterally spaced endless chains, main excavating elements mounted between the chains, scoop-shaped auxiliary excavating elements carried by the chains between which the first-mentioned excavating elements are mounted, said auxiliary excavating elements being open at their rear ends and at their inner sides to discharge the dirt directly into the path of the main excavating elements, and projecting laterally from the sides of the chains and working beyond the sides of the first mentioned excavating elements. 115

4. An excavator comprising laterally spaced endless chains, main excavating elements mounted between the chains, auxiliary excavating elements carried by the chains between which the first mentioned excavating elements are mounted, said aux- 120

iliary excavating elements being open at their rear ends and at their inner sides to discharge the dirt directly into the path of the main excavating elements and projecting laterally from the sides of the chains and working beyond the sides of the first mentioned excavating elements, and being scoop-shaped and comprising a bottom having sides and a back, a shank extending from the top of the inner side and fitting

between adjacent chain links, and fasteners passing through said links and the shank therebetween.

Signed by me at Chicago, Illinois, this 12th day of September, 1914.

JAMES C. FRENCH.
